UNITED STATES PATENT OFFICE.

MARTIN C. REYNOLDS, OF CAREY, OHIO, ASSIGNOR OF ONE-HALF TO RALPH G. SPENCER, OF CAREY, OHIO.

SOFTENING AND FILTERING APPARATUS.

1,080,233.

Specification of Letters Patent.

Patented Dec. 2, 1913.

Application filed September 10, 1913. Serial No. 789,187.

To all whom it may concern:

Be it known that I, MARTIN C. REYNOLDS, a citizen of the United States, residing at Carey, in the county of Wyandot and State of Ohio, have invented a new and useful Softening and Filtering Apparatus, of which the following is a specification.

The device forming the subject matter of this application is adapted to be employed for softening and filtering water used in a boiler, and may be applied to any standard form of feed-water heater now in use.

One object of the invention is to provide novel means for securing a proper mixture of pure water with water saturated with a chemical.

Another object of the invention is to provide novel means for securing a circulation in the device, and for controlling the circulation.

It is within the scope of the invention to improve generally and to enhance the utility of, devices of that type to which the present invention appertains.

With the above and other objects in view, which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawings:—Figure 1 is a sectional elevation of the complete apparatus; Fig. 2 is a vertical longitudinal section of the chemical tank; Fig. 3 is a vertical longitudinal section of the mixing tank; Fig. 4 is a plan of one of the platforms which are located in the mixing tank; and Fig. 5 is a section of the spray head which is located in the feed water heater.

In the drawings there is shown a feed water heater 1 which may be of any desired form, the device herein disclosed being adapted to be attached to any make of feed water heater which might be found in any steam plant. In the present instance, the feed water heater 1 comprises a drum 2, supported upon legs 3 or in any other suitable manner. The heater 1 is equipped with a gage glass 4. An exhaust steam inlet 5 enters one side of the heater 1. In its bottom,

the drum 2 of the heater 1 is provided with 55 a flush pipe 6 which communicates with a sewer (not shown). A hand valve 7 is placed in the pipe 6. Brackets 8 are located in the drum 2 of the heater 1 and support spaced, perforated platforms 9, between 60 which is located a filtering material 10 which may be hay, excelsior or the like. An overflow pipe 11 enters the drum 2 above the uppermost platform 9 and communicates at its lower end with the flush pipe 6. A wa- 65 ter supply pipe 14 enters the top of the drum 2 and is provided at its inner end with a spray head 15. Located below the spray head 15 and supported in the drum 2 are spaced pans 16 of successively increasing 70 diameters. A valve 17 is located in the pipe 14 and is controlled by a link 18, pivotally connected with a lever 19, fulcrumed upon a hanger 20 which may be carried by a pipe 14. A connecting rod 21 is pivoted to the 75 lever 19, the lower end of the connecting rod being pivotally united with a float 22, mounted to move in a casing 23, carried at the upper end of a pipe 24 which enters the drum 2 below the platform 9. The float con- 80 trolled mechanism above described, and another float controlled mechanism to be de- 85 scribed hereinafter may be of any form and there are many structures upon the market which will carry out the ends in view.

The chemical tank is denoted by the numeral 25 and is mounted upon a suitable support 26. A drain pipe 27 enters the bottom of the chemical tank 25, the drain pipe communicating with a sewer (not shown). 90 The chemical tank 25 is equipped with a hand hole 29. Located within the chemical tank 25 are spaced platforms 31 between which is located a filtering material 32 which may be excelsior or any other suitable sub- 95 stance. The platforms 31 are supported by brackets or lugs 31^a and a vertical pipe 33 passes through the top of the chemical tank 35 and through the platforms, the upper end of the pipe 33 carrying a receiving funnel 100 34 for the chemical, there being a screen 35 in the funnel 34. Water is supplied to the funnel 34 by means of a pipe 36, provided with a spray head 37, located within the contour of the funnel 34. The pipe 36 is 105 equipped adjacent its end with a hand valve 38.

The pipe whereby water is drawn from

the heater 1 and conveyed to the boiler is indicated by the numeral 39. Branched from the boiler feed pipe 39 is a pipe 40 which enters the lower portion of the chemical tank 25. In the pipe 40 is a hand valve 41 and a flap or check valve 42 which closes in the direction of the heater 1. Disposed in the pipe 36 is a valve 43, controlled by a link 44, pivoted to the lever 45, fulcrumed upon a hanger 46 which may be carried by a pipe 36. A connecting rod 47 is pivoted to the lever 45 and carries a float 48, operating in a casing 49, supported by a pipe 50 which enters the chemical tank 25 above the platform 31.

The pressure mixing tank is denoted by the numeral 51 and is mounted upon a suitable support 52. The tank 51 is equipped with a man hole 53. Located within the tank 51 are brackets 54, supporting spaced platforms 55, between which is located a filtering material 57. The platforms 55, as shown in Fig. 4, may be made in two or more sections, and may be attached by means of lag screws 56 or the like to the brackets 54. One end of the pipe 36, indicated specifically by the numeral 58 enters the mixing tank 51. Placed in the pipe 36 is a check valve 59 which closes in the direction of the mixing tank 51. A hand valve 30 is also mounted in the pipe 36. A hot water supply pipe 60 communicates with the pipe 36 and is provided with a hand valve 61 and with a check valve 62. One end of the pipe 14, indicated specifically by the reference character 63 enters the mixing tank 51. Interposed in the pipe 14 and located adjacent the tank 51 is a hand valve 64. A water supply pipe 65 enters the mixing tank 51 adjacent its top and communicates with a tank 66. In the pipe 65 is located a cut off valve 67.

The invention further includes a pump 68, the pumping cylinder of which is indicated at 69, the numeral 70 indicating the steam cylinder of the pump. A pipe 71 enters the chemical tank 25 above the platforms 31, the pipe 71 communicating with the pumping cylinder 69. A discharge pipe 72 enters the pumping cylinder 69 and is provided with a hand valve 73 and with a check valve 74. The pipe 72 communicates with a vertical pipe 75, entering the bottom of the mixing tank 51, the pipe 75 being provided with a valve 76, and being adapted to discharge into a funnel 77, when the valve 76 is open, the funnel 77 communicating with a sewer (not shown).

The water supply pipe is indicated at 78 and is provided with a hand valve 79 and a check valve 80, the pipe 78 communicating with the pipe 75. An upright flush pipe 81 enters the bottom of the tank 51 and communicates with the funnel 77, there being a valve 82 in the pipe 81.

The steam supply pipe which communicates with the steam cylinder 70 of the pump 68 is shown at 85 and is provided adjacent the pump with a throttle valve 86. A pipe 87 communicates with the mixing tank 51 and with a pump governor 89 which is interposed in the steam supply pipe 85. The pipe 87 is equipped with a hand valve 88, located between the pump governor 89 and the tank 51.

The circulation through the apparatus is as follows:—From the mixing tank 51, water passes by way of the pipe 14, into the heater 1 and from the heater 1 into the pipe 39 and from the pipe 39 into the boiler (not shown). From the pipe 39, water passes by way of the pipe 40 into the chemical tank 25 and from the chemical tank 25 by way of the pipe 71 to the pumping cylinder 69 and thence by way of the pipe 72 into the pipe 75. The water thus passing into the pipe 75 is charged with a chemical in a manner which will be set forth hereinafter. Pure water traverses the pipe 78 and enters the pipe 75 and thus it will be seen that a mixture of pure water and chemical-laden water is discharged through the pipe 75 into the pressure tank 51 whence the mixture passes into the pipe 14 to repeat the cycle.

The tank 66 is adapted to contain a reserve supply of pure water, and when the system hereinbefore described is installed, the tank 66 may represent an overhead tank which the building is already provided with, it being thus possible to supply the tank 51 either from the tank 66 or from the pipe 78. From the tank 51 water passes by way of the pipe 36 into the funnel 34. The funnel 34 contains the chemical and in this manner the chemical is dissolved and passes by way of the pipe 33 below the platforms 31 in the chemical tank 35. The water charged with chemical rises through the filtering material 32 and passes into the pipe 71, to carry out the cycle hereinbefore described. During the time that the funnel 34 is being charged with chemical, the valve 38 is closed. By adjusting the valves 30 and 61, the latter being located in the hot water pipe 60, the temperature of the water delivered on the chemical in the funnel 34 may be regulated. By opening the valve 76, the operator at any time may ascertain whether or not the supply pipe 78 is clogged.

When the pressure in the mixing tank 51 rises to too great an extent, the pump governor 89 will be operated, to cut off the steam supply to the steam cylinder 70 of the pump 68, and when the pressure falls to a normal point, the pump governor 89 will operate to open the pipe 85, so that steam is again supplied to the pump 68. The water in the heater 1 and in the chemical tank 25 stands at a common level, and this level is maintained by the action of the float 22, the

same controlling the valve 17 which is located in the supply pipe 14 leading to the heater 1.

At times, it may be impossible to maintain 5 a common level in the heater 1 and in the chemical tank 25, owing to the difference in elevation of these two elements. Under such circumstances, it may be impossible for water to flow from the heater 1 into the chemical tank 25 by way of the connecting pipe 40 and then the pipe 40 may be dispensed with. Under the circumstances above pointed out, 10 the entire supply of water to the chemical tank 25 is delivered through the pipe 36, the proper level in the chemical tank 25 being 15 regulated through the medium of the float 48 which controls the valve 43.

The functions of the hand-hole, the gage glass, the several flushing outlets and other 20 common and well known elements need not be entered into in detail, in view of the fact that this specification is addressed to those skilled in the art.

Having thus described the invention, what 25 is claimed is:—

1. In a device of the class described, a chemical tank; a mixing tank; a connection between the tanks; a pump in the connection; a source of pressure supply for actuating the pump; a pump governor in said source and responsive to mixing tank pressure; means for supplying water to the mixing tank; and an outlet for the mixing tank.

2. In a device of the class described, a 35 chemical tank; a mixing tank; a connection between the tanks; a pump in the connection; a source of pressure supply for actuating the pump; a pump governor in said source and responsive to mixing tank pressure; means for supplying liquid to the 40 chemical tank; float controlled means for regulating said supplying means; means for supplying water to the mixing tank; and an outlet for the mixing tank.

3. In a device of the class described, a 45 chemical tank; a mixing tank; a connection between the tanks; a pump in the connection; a source of pressure supply for actuating the pump governor; a pump in said source and responsive to mixing tank pressure; a chemical container communicating with the chemical tank; means for supplying fluid to the container from the mixing tank; means for supplying water to the mixing tank; and an outlet for the mixing tank. 50 55

4. In a device of the class described, a chemical tank; a mixing tank; a connection therebetween; a filter in the chemical tank; a filter in the mixing tank; means for supplying liquid to the chemical tank, below the 60 filter therein, the connection between the tanks opening into the chemical tank above the filter in the chemical tank and opening into the mixing tank below the filter in the mixing tank; means for supplying liquid to 65 the chemical tank below the filter therein; means for supplying water to the mixing tank; and an outlet for the mixing tank.

5. In a device of the class described, a 70 chemical tank; a mixing tank; a connection therebetween; a chemical container communicating with the chemical tank; a pipe communicating with the mixing tank and opening upon the container; a hot water supply pipe communicating with the last specified 75 pipe; valves in the pipes for controlling the temperature of the liquid delivered to the container; means for supplying water to the mixing tank; and an outlet for the mixing tank. 80

In testimony that I claim the foregoing as my own, I have hereto affixed my signature in the presence of two witnesses.

MARTIN C. REYNOLDS.
